Primary Examiner—Raphael Barkai
Attorney, Agent, or Firm—Knobbe, Martens, Olson & Bear, LLP[57] **CLAIM**

The ornamental design for an in-line skate wheel, as shown and described.

DESCRIPTION

FIG. 1 is a perspective view of an in-line skate wheel showing my new design;
FIG. 2 is a top view thereof, the side opposite being identical;
FIG. 3 is a side view thereof; and,
FIG. 4 is a cross-sectional view of the in-line skate wheel along the line 4—4 in FIG. 2.
